TABLE ORNAMENT

Adelaide S. West, Chicago, Ill.

Application June 27, 1955, Serial No. 36,712

Term of patent 14 years

(Cl. D58—11)

Fig. 1

I claim:

The ornamental design for a table ornament, substantially as shown.
